PAIR OF SUNGLASSES

William J. Ruamo, Bridgeville, Pa.
(1530 Park Bldg., Pittsburgh, Pa.)

Filed Oct. 3, 1961, Ser. No. 66,958

Term of patent 14 years

(Cl. D57—1)

Fig.1.

Fig.2.

Fig.3.

Fig.5

Fig. 4

FIG. 1 is a front elevational view of a pair of sunglasses showing my new design, wherein the dot and dash outline of a pair of eyeglass lenses is for illustrative purposes only;

FIG. 2 is a top view thereof;

FIG. 3 is a rear, elevational view thereof;

FIG. 4 is a cross-sectional view thereof taken along line IV—IV of FIG. 1; and

FIG. 5 is a perspective view thereof taken from the left of FIG. 1.

I claim:

The ornamental design for a pair of sunglasses, substantially as shown and described.
